CLAIM

The ornamental design for a children tricycle, as shown and described.

DESCRIPTION

FIG. 1 is a first perspective view of a children tricycle showing my new design;

FIG. 2 is a second perspective view thereof;

FIG. 3 is a third perspective view thereof;

FIG. 4 is a front view thereof;

FIG. 5 is a back view thereof;

FIG. 6 is a left side view thereof;

FIG. 7 is a right side view thereof;

FIG. 8 is a top view thereof;

FIG. 9 is a bottom view thereof;

FIG. 10 is a perspective view of another state of the children tricycle thereof;

FIG. 11 is a perspective view of another state of the children tricycle thereof; and,

FIG. 12 is a perspective view of another state of the children tricycle thereof.

The broken lines shown in the drawings depict portions of the children tricycle that form No part of the claimed design.
